CLAIM

The ornamental design for a flexible interconnecting member for solar cells, as shown and described.

DESCRIPTION

FIG. 1 is a top perspective view of a flexible interconnecting member for solar cells showing our new design;

FIG. 2 is a top plan view thereof;

FIG. 3 is a bottom plan view thereof;

FIG. 4 is a front elevation view thereof, the rear elevation view being a mirror image; and,

FIG. 5 is a right side elevation view thereof, the left side elevation view being a mirror image.

The broken lines shown represent environmental structure and form no part of the claimed design.
